CLAIM

The ornamental design for a display screen with animated graphical user interface, as shown and described.

DESCRIPTION

FIG. 1 illustrates a view of a display screen with animated graphical user interface showing the first image of my new design; and,

FIG. 2 shows a second image thereof.

The appearance of the animated graphical user interface sequentially transitions between the images shown in FIGS. 1-2. The process or period in which one image transitions to another image forms no part of the claimed design.

The outer perimeter illustrated by dashed broken lines in the drawings illustrates a display screen and form no part of the claimed design. The remaining broken lines in the drawings illustrate portions of the graphical user interface and form no part of the claimed design.

1 Claim, 2 Drawing Sheets
